PROTECTIVE GAP FOR ELECTRICAL EQUIPMENT

Application filed December 30, 1929. Serial No. 417,468.

This invention has to do with an arrester or protective gap for electrical equipment, and it is an object of the invention to provide a device of this character which is efficient and dependable in low voltage lines and capable of handling high currents over comparatively long periods of time.

In various fields of electrical development there is need for an arrester that will operate 10 at relatively low voltages and yet have high current carrying capacity over comparatively long periods of time. The situations in which such devices may be used further require uniform voltage breakdown and ability 15 to properly clear the circuit after operation. Arresters such as we refer to are needed particularly in connection with telephone lines, and the like, which are subject to high between-wire-voltages and high voltage to 20 ground. In lines or circuits of this type where continuity of service is essential, it is not satisfactory to protect the equipment or instruments by fuses which disconnect or open the circuit until a new fuse is installed. 25 Arresters that are on the market available for use and capable of functioning properly on low voltages will carry 20 or 25 amperes for only a second or two. A longer application of such amperage destroys the arrester.

It is an object of the present invention to provide an arrester suitable for use in low voltage circuits and capable of effectively and dependably handling high currents over comparatively long periods of time. An embodiment of the invention, which has been successfully operated, protects a low voltage telephone circuit and will carry 20 to 25 amperes for a period of 12 to 15 minutes without 30 breaking down or being damaged.

Another object of the present invention is to provide a construction for a gap arrester whereby heat generated by arcing in the arrester is rapidly and effectively removed 35 from the points of arcing in a manner to prevent overheating of the tips of the electrodes.

Another object of the invention is to provide a combination of materials in a gap arrester which provides a practical, efficient 40 and inexpensive device that will handle an

arc dependably over a long period of time without the electrodes being damaged.

A further object of the invention is to provide a gap arrester having electrodes with flat polished faces over which an arc will 55 spread rather than concentrate at one point.

Another object of the invention is to provide a gap arrester having electrodes with flat polished faces without edges or joints 60 at which an arc will concentrate.

The various objects and features of our invention will be best and more fully understood from the following detailed description of a typical form and application of the 65 invention, throughout which description we refer to the accompanying drawing, in which:

Fig. 1 is an exterior elevation of the gap arrester provided by the present invention 70 showing it arranged in a suitable mounting. Fig. 2 is a detailed transverse sectional view of the arrester being a view taken as indicated by line 2—2 on Fig. 1. Fig. 3 is a longitudinal detailed sectional view through one of the electrodes of the arrester being a view taken as indicated by line 3—3 on Fig. 2, and Fig. 4 is a detailed transverse sectional view 75 taken as indicated by line 4—4 on Fig. 1.

The present invention provides an arrester useful in various circuits and intended particularly to handle low voltage circuits and yet be capable of carrying a comparatively high amperage over a substantial period of time. A telephone line subject to 80 high between-wire-voltage and high voltage-to-ground presents a typical situation in which the present arrester can be used to advantage. We will therefore proceed with a detailed description of a form of the invention which has been successfully used in a telephone circuit such as we have just referred to, it being understood that the invention contemplates various changes or modifications to make the device suitable for 85 various special or unusual situations.

The arrester comprises, generally, two electrodes A and B mounted in spaced relation so that there is the desired spark gap between their tips. In the drawing we have 90 shown a mounting for the electrodes includ- 100

ing a support or frame 10 of suitable insulating material having spaced abutments 11, a spacer 12 between the inner or adjoining ends of the electrodes, and springs 13 at the outer ends of the electrodes and engaging the abutments 11 of the frame to hold or urge the electrodes inwardly so that the spacer is clamped between them.

The present invention resides primarily in the electrodes, and as both electrodes may be the same, we will proceed with a detailed description of a single electrode, it being understood that such description may apply to both.

The electrode provided by the invention includes, generally, a core 14 formed of a material which is a good electrical conductor and also a good heat conductor, a tip 15 on the inner or gap end of the core forming a flat, smooth gap face of considerable area and formed of material which is a good electrical conductor and which is not readily impaired or injured by heat, and a body 16 in connection with the core and formed of material causing it to act as a receiver or absorbing element for the heat conducted by the core.

The core 14 may be in the form of an elongated member or bar having one end suitable for carrying the tip 15 and having a part adapted to receive the body 16. In the preferred form of the invention illustrated the core 14 is in the nature of a bar round in cross section and sufficiently long to have a large direct bearing engagement with the body 16, as will be hereinafter described. The invention provides that the core be formed of material which is a good electrical conductor and at the same time capable of rapidly conducting heat. In practice we have found it advantageous to form the core of copper as such material is an excellent electrical conductor and has a high heat conductivity.

The facing or tip 15 provided on the inner or gap end of the core is preferably applied or formed directly on the end of the core and is formed of a material which will not melt or break down under the arcing conditions under which the device operates. In practice we have found it advantageous to use a high grade of rolled silver in the formation of the tip 15 and have used silver solder in applying the tip to the copper core. The tip is finished to have a smooth flat face 17 of a suitable area forming a sparking surface. In practice we make the face 17 smooth by polishing it. When we use the term "flat smooth surface" we mean a finely finished plane surface such as a polished plane surface, as distinguished from a surface of ordinary finish and from a surface that is more or less granular or has cracks, seams or joints in it. In other words the surface is made to possess such degrees of firmness and smoothness that the arc instead of centering or concentrating

at one or more points spreads more or less uniformly over the entire surface. Silver not only effectively resists heat but also has a high heat conductivity, and therefore heat generated by arcing at the face 17 is effectively transmitted or conducted through the tip to the core. The tip 15 is formed so that its face is free of cracks or joints and so that it has no edges at which arcing will concentrate. In practice the margin or edge portion of the face is rounded or beveled as shown in the drawing.

The body 16, provided for absorbing or receiving the heat from the core may be a comparatively large element or block carried directly on the core to have a long bearing contact with the core. In the construction illustrated the body 16 is in the form of a large block of material having an opening 20 through it accurately receiving the core 14. The body 16 is split at 21 and provided with clamp bolts 22 which may be operated to tighten the body onto the core to assure a tight bearing engagement between the core and body. In practice one of the bolts 22 may be extended for use as a terminal or binding post for the electrode, as shown in the drawing. In practice we have found it advantageous to form the body 16 of cast iron as such material has a high heat storage capacity and will readily receive heat from the core 14 in the desired manner. Further, cast iron is a material which is inexpensive and which can be advantageously finished or machined in the manner above described.

The spacer 12, which we have shown as interposed between the inner ends of the electrodes to space the electrodes so that there is the desired gap between their tips, may be an annular body or ring of insulating material. In the construction illustrated annular projections 25 are provided on the inner ends of the bodies of the electrodes to fit into the insulating ring or spacer 12 to properly guide the spacer with reference to the electrodes, as clearly illustrated in Figs. 1 and 2 of the drawing. By making the spacer 12 of the desired width or length, it operates to space the electrodes so that the faces 17 of the electrode tips are parallel and the desired distance apart. The ends or bearing faces of the spacer are ground so that they are truly parallel and thus space the electrodes with their faces in true parallelism. It will be obvious that the flat smooth faces 17, being thus arranged parallel with each other, form a uniform gap.

In the particular mounting arrangement shown, the springs 13, which operate to clamp or hold the electrodes together on the spacer 12, may be guided by suitable projections 26 on the outer ends of the bodies 16 of the electrodes and may be held in suitable recesses 27 provided in the abutments 11 of the frame.

The construction which we have described

has been found to operate dependably and effectively under conditions such as we have referred to above and constitutes a practical solution for a problem which has been heretofore unsolved. It is to be particularly noted that the construction is simple and inexpensive of manufacture and it will be obvious that it is capable of considerable modification or variation to suit varying conditions. Under actual operating conditions an arc occurring between the faces 17 is spread and does not concentrate at any one spot. The invention thus distinguishes over constructions in which the electrode faces have cracks or joints in them or have sharp edges. Further, by using polished silver faces we eliminate pitting of the gap faces such as occurs with the use of certain materials, for example, carbon. The storing or absorbing body being in direct contact with the conductive core causes the heat to be handled so that the gap operates dependably and effectively.

Having described only a typical preferred form of our invention, we do not wish to limit ourselves to the specific details set forth, but wish to reserve to ourselves any changes or variations that may appear to those skilled in the art or fall within the scope of the following claims.

Having described our invention, we claim:

1. A protective gap for use in connection with an electric circuit including, an electrode having a core of high heat conducting capacity and having a flat polish silver gap face, and a metal body of large volume relative to the core and of high heat absorbing capacity directly engaged around the core.

2. A protective gap for use in connection with an electric circuit including, an electrode having a core of high heat conducting capacity, a silver tip on the core having a flat smooth polished gap face, and a metal body of high heat absorbing capacity in direct connection with the core.

3. A protective gap for use in connection with an electric circuit including, an electrode having a core of high heat conducting capacity, a tip of silver on the core presenting a flat smooth polished gap face, and a large metal body of high heat absorbing capacity in direct connection with the core.

4. A protective gap for use in connection with an electric circuit including, an electrode having a copper core, a silver tip on the core having a flat polished gap face, and an iron body engaged around the core, the body being of substantial bulk with respect to the core and having a large direct bearing engagement with the core.

5. A protective gap for use in connection with an electric circuit including, two electrodes each including a copper core, an iron body, the body being split and engaged directly around the core, and a screw member operating to clamp the body on the core and

forming a terminal for making electric connection with the electrode, and silver tips on the cores having flat polished parallel gap faces.

6. A protective gap for use in connection with an electric circuit including, two electrodes each having a core and a heat absorbing metal body surrounding the core and in direct engagement therewith, silver tips on the electrodes having spaced parallel polished gap faces, and a spacer of insulating material between the electrodes, the spacer being in engagement with the said bodies of the electrodes, the ends of the spacer being perfectly parallel and accurately fitting against the electrodes to maintain the gap faces in perfect parallelism.

7. A protective gap for use in connection with an electric circuit including, two electrodes each having a core and a heat absorbing metal body of large volume relative to the core surrounding the core and having direct engagement with the core, silver tips on the cores having parallel polished flat gap faces, and a spacer ring of insulating material between the electrodes the spacer being in engagement with the said bodies of the electrodes, the bodies of the electrodes having parts projecting into the ring.

8. A protective gap for use in an electric circuit including, two electrodes having spaced absolutely parallel flat smooth highly polished silver faces, and heat absorbing means in connection with the electrodes.

9. A protective gap for use in an electric circuit including, two electrodes, and rolled silver tips on the electrodes having spaced parallel flat smooth polished faces, the margins of which are free of sharp edges, and heat absorbing means in connection with the electrodes.

10. A protective gap for use in an electric circuit including, two spaced cores of heat conducting material, silver tips on the adjoining ends of the cores, the faces of the tips being parallel polished smooth and flat, and comparatively large heat absorbing bodies directly connected with the cores.

In witness that we claim the foregoing we have hereunto subscribed our names this 20th day of December, 1929.
